ABSTRACT: A weighted rod and a coacting contact carrier frictionally entrainable by a mounting on a rolling craft generate timing signals in positions of maximum lateral excursions of craft with reference to a longitudinal axis, the rod being pivotally mounted aboard the craft on a shaft parallel to that axis so as substantially to maintain a vertical reference position whereby two sets of contacts on these relatively movable members are alternately closed during respective half-cycles of the rolling motion. The timing signals control the operation of an antiroll system, specifically two stabilizer tanks on opposite sides of the craft which are alternately filled with and drained of water and which are supplemented by a further pair of tanks whose relative water volume is altered to balance deviations of the mean attitude of the craft from an upright position as likewise determined from these timing signals.

ANTIROLL FACILITIES

Antiroll devices comprise means which produce torques opposing the roll of seagoing ships and other craft and which are controlled so that the stabilizing action anticipates the roll movement. Accordingly, the control is usually effected by appropriate means responsive to the angle of tilt of the ship, the rate of change of such angle and possibly the acceleration of the variation and the differential thereof. The counter-torque-producing means can be dynamic—i.e., act in accordance with the ship's speed of travel—and in such cases are usually ailerons which project from either side of the craft. The ailerons can be permanently extended in rough weather and adjusted by variation of their inclination or pitch angle, or they can have a fixed orientation but be retracted or extended to a variable degree; ailerons are also known whose effective length and orientation are fixed but which are brought out for varying periods of time.

Such stabilizing means can also be static, i.e. based on the weight of shiftable masses. It has already been suggested that moving masses of liquid be used for this purpose, to which end vessels are disposed along the edges of the ship symmetrically with reference to its axis; a mass of water is then transferred from a vessel or tank on one edge to a tank on the other edge at appropriate times. The disadvantage of this solution is that the water-transfer operations require very large energies. To obviate this disadvantage, it has been suggested that the tanks be disposed below the water line and that external water be allowed to enter the tanks and be expelled therefrom in the rhythm of the rolling motions to be counteracted. This measure avoids the expenditure of energy for the transfer of water from one side of the ship to the other; the tanks can be filled just by hydrostatic pressure with an increase of delivery if the filling orifices are appropriately oriented, and the power required is merely that necessary for emptying the tanks with the aid of compressed air. Such stabilizers have a considerably larger time constant than systems operating with extendable and/or orientable ailerons or fins.

Rolling can be considered a combination of two phenomena resulting in a composite oscillatory motion: a natural oscillation of the craft about its longitudinal axis, with a periodicity which is fairly constant although dependent upon the loading of the ship and the swell of the sea, and a forced oscillation caused solely by the swell and superimposed upon the natural oscillation of the ship with, usually, a much longer periodicity. Theoretical studies of these movements show that an antiroll device can be controlled in response to data relating to oscillations immediately preceding the oscillations to be damped, such as the times of occurrence of the peaks, the length of a half-period, the roll amplitude and the mean position of the ship.

The general object of our present invention is to provide means for obtaining some or all of these various data and using them to control antiroll stabilizers. More particularly, our invention aims at providing means for forecasting the rolling movement to be stabilized from the motion, during the immediately preceding complete roll cycle, of a vertical reference standard aboard the craft.

In its broader aspects, our invention provides a reference member of substantially fixed absolute orientation maintained by gravity or inertia, a cooperating member mounted on the craft for lateral angular entrainment, and coacting circuit means on these members for actuating a stabilizer-control system in timed relationship with the relative movement of the members.

According to a more specific feature of our invention, a rocking member or plummet swivable around at least one longitudinal axis relatively to the ship while maintaining a substantially vertical position is associated with a balanced unit movable around an axis coincident with the swivel axis of the rocking member, this unit bracketing the rocking member with play and comprising on each side thereof a contact member operated by the interengagement of the rocking member and the mobile unit. In a device of this kind, there occurs at each peak of a transverse oscillatory movement of the

ship a switchover of contacts carried by the coacting elements so that a control signal is generated to indicate the time of occurrence of such peak.

Preferably, such a rocking member supports at least one slider movable along a track of a DC-energized potentiometer connected with the ship, the voltage thus taken from the potentiometer in certain positions being stored to furnish an analogue output representing one of the parameters of the oscillating movement. Consequently, a comparison of the extreme voltages obtained in the rocking movement enables their mean value to be ascertained, as a measure of the mean attitude or angle of heel of the ship, as well as their difference which is a function of roll amplitude.

According to another feature of the invention, roll compensation is produced by two independent torque generators respectively responsive to the natural roll of the ship and to the oscillation superimposed thereupon, only the torque generator counteracting the natural roll of the ship being controlled in dependence upon roll amplitude whereas the other torque generator is controlled only in dependence upon the mean position of the ship between two consecutive opposite peaks of the oscillation. This technique assumes, with good approximation of reality, that the lower-frequency oscillation superimposed upon the natural roll of the ship is a determining factor only for the mean position of the craft around which the oscillations occur, but that the amplitude of the composite motion in practice depends only upon the natural oscillation of the ship about its longitudinal axis.

Although the principles explained above have general applicability, we shall particularly describe hereinafter their utilization with antiroll torque generators of the two types referred to above.

In the accompanying drawing:

FIG. 1 is a diagrammatic plan view of antiroll damping equipment comprising tanks communicating with a body of liquid surrounding a craft;

FIG. 2 is a cross section on the line II-II of FIG. 1;

FIG. 3 is a cross section on the line III-III of FIG. 2;

FIG. 4 is a view in diagrammatic cross section of a ship having aileron-type antiroll equipment;

FIG. 5 is a side view on the line V-V of FIG. 4;

FIG. 6 is a diagram showing the operating conditions of a tank-type stabilizer as illustrated in FIGS. 1-3;

FIG. 7 is a block-schematic view of a system for controlling a tank-type stabilizer of the kind shown in FIGS. 1-3;

FIG. 8 is a partly diagrammatic side elevation of a device for providing a vertical reference standard and of associated electrical circuitry;

FIG. 9 is a side view on the line IX-IX of FIG. 8;

FIG. 10 is a diagrammatic view of the device shown in FIGS. 8 and 9, along with its electrical circuit connections;

FIG. 11 shows a circuit diagram for evaluating the data obtained from the assembly of FIGS. 8-10;

FIG. 12 is a graph showing variations in the operating time of a torque compensator plotted against the amplitude of the roll to be compensated;

FIG. 13 is a circuit diagram, more detailed than FIG. 7, of a control system for a tank-type stabilizer as shown in FIGS. 1-3;

FIG. 14 is a diagram showing how the system of FIG. 13 operates in dependence upon the real amplitude of the roll to be corrected;

FIG. 15 is a diagram of an installation for correcting the mean angle of heel of a ship;

FIG. 16 is a diagram of a balanced amplifier for the circuit of FIG. 11;

FIG. 17 is a simplified alternative form of circuit diagram for providing a control signal after a quarter-period of the natural roll;

FIG. 18 is a diagram serving to explain the operation of the system shown in FIG. 17; and

FIGS. 19 and 20 are diagrams serving to explain the use of aileron-type torque correctors for counteracting rolling motion.

FIGS. 1-5 show conventional antiroll devices in which the invention may be of use.

A ship 1 shown in FIGS. 1-3 has tanks 2_B and 2_T disposed along its port and starboard sides, the subscripts B and T standing for the French designations babord (port) and tribord (starboard). Each tank is formed with two orifices 3, 4, the orifice 3 being open toward the front and the orifice 4 being open toward the rear of the craft. Since all these orifices are disposed below sea level 5, the tanks can be filled through the orifices 3 by both hydrostatic and dynamic pressure; when the ship is moving, emptying of the tanks is assisted by the dynamic negative pressure produced in the rear of the orifices 4.

The tanks can be filled by venting their interior to atmosphere via conduits 6 and valves 7. The tanks are emptied by means of compressed air supplied from a reservoir 8 by a pump 9; valves 10, 11, controllable by suitable servomechanisms, also intervene in the filling and draining of the tanks.

In the construction shown in FIG. 1, the ship has two pairs of tanks, which can be operated simultaneously, on each side. As shown hereinafter, each individual tank of these identical pairs may advantageously be controlled independently.

In the antiroll installation shown in FIGS. 4 and 5, actuators 12 can extend ailerons or fins 13 of hydrofoil profile from opposite sides of the craft; with proper angular orientation, these fins can provide uplift or downthrust compensating for the rolling motion and varying as a function of the forward speed of the craft. The pitch of these fins and/or their effective length L, i.e. the degree of their projection from the sides of the craft, may be controlled by conventional means.

Systems using stabilizing masses, such as the tank-type stabilizer shown by way of example in FIGS. 1-3, are operative whether the ship is stationary or moving (being more effective when the ship is in motion than when it is not), but aileron-type stabilizers are operative only when the ship is moving.

In the ensuing description of FIGS. 7-16 we shall, for convenience, limit ourselves to a discussion of tank-type antiroll stabilizers of the kind shown in FIGS. 1-3 whose damping effect depends upon the state of tank filling, thus upon a continuously varying quantity, so that an appreciable time factor intervenes in the antiroll action, in contradistinction to the almost instantaneous compensating effect of fin-type stabilizers.

It will be assumed that the filling and emptying of the tanks proceeds at a constant rate and that the lever arm of the tanks relative to the longitudinal axis of the ship is the same for all angles of roll up to a limiting value of approximately 15°. The stabilizing torque developed by each tank can therefore be represented by a sequence of linear functions of time.

In the case of a simple roll the compensating action provided by the tanks can be represented in the manner shown in FIG. 6, where the time axis t represents the mean vertical position of the ship and the roll angles θ on either side of this mean vertical position are plotted along the ordinates, up for one side (e.g. port) and down for the other. A sinusoidal line 14 can therefore represent the simple or natural roll having, as an undamped oscillation, a natural period T_o . To damp this assumedly large oscillation when the angle of heel on either side is a maximum, i.e. when the bridge has its greatest list toward such side (e.g. to port as shown at time $t = 0$ in FIG. 6) and the ship starts to straighten, the corresponding side (here the port side) of the ship must be weighted to limit the restoring or straightening torque and thus to attenuate the oscillation. On the other hand, when the ship passes through its normal position before tilting to the other side at an angular velocity which is then at its maximum, it must be lightened to reduce the mass actually performing the oscillating movement. To achieve maximum damping, therefore, the tanks must be filled when the ship reaches its greatest angle of heel, whereupon the rising tanks just filled should be drained as soon as the mean position is reached.

Consequently, as FIG. 6 shows, the tanks on each side can start receiving liquid at the time when the angle of heel to such side is a maximum lateral excursion. Since the filling rate is

considered constant, a straight line 15₁ can represent filling. The voiding of the same tank can start at a time t_r near the point $T_o/4$ corresponding to the passage of the sinusoidal line 14 through zero, with a straight line 16₁ representing drainage. The volume of water used in this case for stabilization corresponds to the triangle bounded by the abscissas t and the straight lines 15₁, 16₁, which represent the stabilizing torque on a convenient scale.

However, this correction may sometimes be excessive and, if the roll is of low amplitude, may make the ship oscillate. In this case the refilling must start at an instant, such as t_r , after the time of maximum angle of heel, with voidance still commencing at a time t_r near $T_o/4$. The roll compensation provided on each side then corresponds to the hatched triangles whose sides 15₂, 16₂ are parallel to the maximum-correction sides 15₁, 16₁.

FIG. 12 illustrates this variation of damping in graph form.

As already stated, the tanks have more effect when the ship is moving than when it is not. If the start of tank filling at maximum tilt on either side produces a damping α_o when the ship is stationary and β_o when the ship is moving (the angle α_o being 2° and the angle β_o being 3° by way of example), the damping factor AM is zero when the instant t_r of incipient refill, occurring at time $T_o/4$, coincides with the instant t_r of incipient voiding. It will be assumed, in close approximation to the actual facts, that a shift of the time t_r between the antinodal and nodal points 0 and $T_o/4$ causes a variation of the damping factor AM as represented by the straight line D_r. This linear variation of damping in dependence upon t_r (delay in the start of filling relative to peak time 0) is significant for the interpretation of the graph of FIG. 14 discussed hereinafter.

As shown in FIG. 6, the periodically recurring corrective action of the antiroll system is out of phase with the oscillation θ to be compensated, a factor which modifies the period of such oscillation. The true oscillation period will be designated hereinafter by the reference character T.

As already stated, however, rolling is a composite movement resulting from a combination of the natural roll of the ship sustained by external forces, with a superposed sway produced by the swell.

According to a feature of our invention, this complex movement is considered as a simple oscillation whose mean line is not the axis t but a curve 17 (representing an oscillatory phenomenon of amplitude θ_M) determined graphically by the sequence of mean ship positions relative to the horizontal (or the vertical) between two consecutive swings in opposite lateral directions. Full roll correction therefore comprises at any time a correction of the ship's side-to-side movement and a correction of the ship's mean position, i.e. a rebalancing relative to its longitudinal axis, so as to oppose the slow movements tending to tilt the ship to one side or the other. This latter correction can be achieved by varying the state of filling of a pair of balancing tanks (2B₂, 2T₂ in FIG. 7) under the control of a signal representing the mean attitude of the ship between two extreme positions on opposite sides.

We shall describe hereinafter how such a signal can be generated.

Correction of side-to-side movement of the ship depends for each side upon a determination of the instants t_r and t_r which are in turn dependent upon the times $t = 0$ when the roll reaches its maximum excursion alternately on each side, upon the half-amplitude θ_n of the roll which determines the required degree of damping and therefore the delay between the instants t_r and antinodal points 0, and upon the mean tilt angle θ_M of the ship compared with its actual list θ to determine the time t_r , thus obviating the need for direct determination of the duration of each quarter-period after passage through the peak.

The installation can be realized as schematically shown in FIG. 7.

Associated with a vertical reference standard VR articulated around a pivotal axis parallel to the ship's longitudinal axis is an electromechanical unit MI which signals the instants

t_o marking the antinodal points for port and starboard, along with signals θ_n , θ_M and θ_n , θ_M and θ , which are passed to two controllers CaB (for port) and C_nT (for starboard) sharing a common section CV. From these data the controllers determine the starting times $t_r(B)$ and $t_r(T)$ for the filling of the corresponding tanks 2B₁ and 2T₁ by the energization of the respective electromagnetic valves EB and ET, while the common control circuit CV determines the starting time t_r for the subsequent emptying by breaking the valve-energizing circuit so that the compressed air can expel the water from the tanks.

The signal θ_M , an analogue of the mean angle of the ship relative to the vertical, also goes to a regulator AS receiving feedback information on the liquid levels in the tanks 2B₂ and 2T₂ whose state of filling is controlled by this regulator through respective electromagnetic valves FB and FT.

When the ship is balanced and there is no angle of heel, the two main tanks 2B₁, 2T₁ are full. The maximum restoring torque in either sense is of course produced by emptying a single main tank, i.e. the one on the side where weight has to be reduced. A similar variation restoring torque can be produced either by emptying some liquid from one of the two supplemental tanks 2B₂, 2T₂ or by introducing an equivalent quantity of liquid into the other supplemental tank.

FIG. 15 shows a circuit arrangement for the regulator AS. A voltage e_M , which is an analogue of θ_M (obtained in a manner described hereinafter), is zero when the mean position of the ship is horizontal, positive for a mean angle of heel to one side, and negative for an opposite mean tilt; this voltage is fed to two windings 81_B and 81_T of two polarized relays whose armatures 82B, 82T control via intermediate relays (not shown) the electromagnetic valves FB and FT, respectively; the two armatures could also be replaced by a single contact arm.

At their other ends the windings 81_B, 81_T are supplied with voltages tapped from respective potentiometers 83_B, 83_T by sliders 85_B, 85_T under the control of level-indicating floats 84_B, 84_T in tanks 2B₂, 2T₂, respectively.

The reference voltage is therefore zero for both tanks when the same are full; the potentiometer 83_B delivers a positive voltage which increases in proportion to the drainage of tank 2B₂, whereas potentiometer 83_T under the same condition delivers an increasing negative voltage. Consequently, if the mean angle of heel is e.g. to starboard (e_M negative), tank 2T₂ continues to drain as long as the absolute value of e_M exceeds that of the voltage on the slider 85_B, but fills in the opposite case.

FIGS. 8—11 show the assembly VR — MI, i.e. the means for obtaining the data t_o , θ_n , θ_M and θ .

The vertical reference direction can be provided by a gyroscope or more simply by a pendulum or plummet 18 oscillating around a shaft 19 with negligible friction, shaft 19 being borne by the ship and extending parallel to the longitudinal axis thereof. To compensate for pitching, the shaft 19 can be mounted in a collar 19' journaled on a shaft 19'' extending transversely of the ship. Mounted coaxially with shaft 19 is a mobile unit 20 rotatable with low friction in a bearing 21 rigidly secured to the mounting 112 for the shaft 19'' and centered on the pivotal axis of pendulum 18; the unit 20 is balanced around its axis and is provided, on opposite sides of the pendulum rod 18, with contact points 21₁, 21₂, whose spacing can be adjusted by means of a screw 22 spreading their resiliently biased supporting arms.

The contacts 21₁, 21₂ are adapted to cooperate with a conductive ferrule 23, mounted on the pendulum rod, energizable via a conductor 24 connected to the shaft 19. The circuit is therefore closed externally either via a conductor 25, connected to contact 21₁, or via a conductor 25₂ connected to contact 21₂. Rod 18 also carries ferrules 26, 27 which are connected to conductors 28, 29 and respectively slide along potentiometer tracks 30, 31 of resistance material rigid with frame 119.

With the friction of the mobile unit 20 in its bearing 21 slightly greater than the pendulum friction, and with the weighted rod 18 staying substantially vertical throughout the

oscillations of the craft, ferrule 23 abuts either of the points 21₁, 21₂ and remains in contact therewith to its position of maximum tilt. On the other hand, as soon as the return swing starts, the ferrule 23 withdraws from the engaged contact and abuts the other one. Consequently, upon each reversal one contact opens, with closure of the other contact after a time interval which can be adjusted by means of the screw 22.

Thus, the times t_o of maximum port and starboard tilt can be determined by means of the set of contacts 23, 21₁, 21₂.

As FIG. 10 shows, the potentiometer tracks 30, 31 furnish analogue voltages for the values of θ_n , i.e. the half-amplitude of the lateral oscillation of the ship, and of θ_M , i.e. the position relative to the vertical of the bisector of the stroke angle $2\theta_n$ measured during each oscillatory period.

The ends of the arcuate tracks 30, 31 are respectively connected to ground potential (0) and to a fixed operating potential A, the polarity of the voltage drop being opposite for the two tracks.

Let us assume that 18_a and 18_b represent the two end positions of the plummet 18 and its sliders 26, 27 relative to the resistor strips 30, 31. If a and a' are the potentials of the contactors 26 and 27 in the position 18_a, and b and b' are the corresponding potentials in the position 18_b, the relationships

$a' = A - a$ and $b' = A - b$
exist between these two output voltages of generator 26 — 31 which are thus seen to be mutually complementary. Consequently, if the magnitudes of a' and of b are stored in the two limiting positions, the mean value e of the potentials will be

$$e = \frac{a' + b}{2} = \frac{A}{2} + \frac{b - a}{2}$$

whence

$$\frac{b - a}{2} = e - \frac{A}{2}.$$

Thus, the voltage $V\theta_n = e - \frac{A}{2}$ is the analogue of the half-amplitude θ_n of the swing between the positions 18_a and 18_b.

Similarly, if we consider the potentials derived from a single track, e.g. the track 30, in the end positions 18_a and 18_b, the mean potential is $\frac{a + b}{2} = d$.

The mean position θ_M can therefore be represented by an analogue voltage $V\theta_M = d - \frac{A}{2}$ corresponding to the input voltage e_M of FIG. 15.

FIG. 11 shows the basic design of the memory used to store maximum-swing potentials and to deduce the mean of the data thus stored. The potentials, e.g. a and b , to be stored are transmitted via respective amplifiers A_M to contacts k_{B1}, k_{T1} from the corresponding slider 26 and/or 27 of FIG. 10. The windings of relays K_B and K_T are connected, in circuits of short time constant (compared with period T or T_o), to two normally charged capacitors G_B and G_T. At the instants corresponding to maximum angles of heel to port and starboard, respective contacts m_B, m_T are closed, in a manner described hereinafter, under the control of the contacts 21₁, 21₂ to complete respective discharge paths. The windings K_B, K_T are therefore very briefly energized at the appropriate time so that the short closure of their contacts k_{B1}, k_{T1} alternately charges two identical capacitors H_B, H_T to the assigned potentials. The latter capacitors are serially interconnected by a pair of equal resistances r_a.

If we neglect leakage losses of the two capacitors H_B and H_T after their charging time, the mean d of their stored voltages appears at the junction M of resistors r_a and also yields the analogue voltage $V\theta_M = e_M = d - \frac{A}{2}$ supplied to the system AS of

FIG. 15.

For rapid charging of the capacitors H_B, H_T and to make voltage e_M available throughout half an oscillation period, the amplifiers A_M shown in FIG. 11 may be of the balanced type as shown in FIG. 16. A voltage u of low value, which can be either positive or negative, is applied in parallel to two

transistors 87, 88 which are similar to each other, except that transistor 87 is of the NPN type and transistor 88 is of the PNP type, and which are connected as emitter followers (with collectors at fixed potentials) by way of two resistors 89, 90 connected to zero potential. One or the other of the transistors conducts according to the polarity of the input voltage u is also present, without amplification but developed across a low impedance, at the common output terminal 91 of the transistors.

Circuit arrangements similar to the one shown in FIG. 11 are also used, as described hereinafter, to produce the voltage $e_n = V\theta_n$. However, since these circuit arrangements are to establish a precise instant voltage measurement, the connection between the two symmetrical resistances is not permanent but is completed only momentarily to determine such instant (see FIG. 13); also, in order that the voltages collected by the storage capacitors may be independent of previous charges received thereby, the capacitors are periodically discharged before being recharged to the new voltage to be stored. These circuit arrangements also use amplifiers A_m for charging the storage capacitors.

The voltage e_n (which is alternately positive and negative) departs further from zero than does the voltage e_M . As will become apparent hereinafter, the circuit arrangement A_m operates satisfactorily as long as the ratio of its input and output voltages is linear at least for low values of e_n , since in the case of higher voltages e_n —i.e., large oscillations of the ship—the system operates continuously with maximum effect and exact correspondence between input and output voltages becomes unimportant.

The circuit arrangement shown in FIG. 13 uses the basic systems hereinbefore described to obtain voltage analogues for θ, θ_n (for both port and starboard), θ_M and for determining the times $t_r(B), t_r(T)$ and t_r . In FIG. 13 all relay contacts are shown in the unoperated position. Connected to contacts 21₁ and 21₂ are the windings of respective relays M_B, M_T which are therefore energized alternately, each substantially for half an oscillation period between two maximum excursions, and are then deenergized for the remainder of the cycle. Each of the these relays comprises a reversing armature 35_B, 35_T and a circuit-closing armature 36_B, 36_T. Each reversing armature, by changing over from its back contact m_{B1} or m_{T1} to its front contact m_{B2} or m_{T2} , enables the capacitor G_B or G_T to charge through one of two like resistances r_n , for subsequent discharge via the relay windings K_B and K_T , respectively.

Each armature 36_B, 36_T completes, by way of a respective front contact m_{B3} or m_{T3} , a circuit for supplying a negative energizing voltage to the controllers C_aB and C_aT . These circuits are closed by armatures D_{B1} and P_{T1} of respective relays P_B and P_T which are alternately energized by a reversing armature 37 of a polarized relay 39 in control circuit CV, this armature 37 moving toward one or the other of two bank contacts 38₁, 38₂, depending upon the direction of current flow through its winding. The mode of energization of this winding will be described later.

The relays K_B and K_T each comprise, in addition to their respective armatures k_{B1} and k_{T1} (see FIG. 11), two other armatures k_{B2}, k_{B3} and k_{T2}, k_{T3} , respectively, through which the voltage a' can be stored in respective capacitors CB_1, CT_1 and the voltage b can be stored in respective capacitors CB_2, CT_2 . The capacitors CB_1, CB_2 associated with the port controller C_aB cooperate with a pair of equal resistances r_c to form a voltage divider similar to the one shown in FIG. 11. However, the two resistors r_c , instead of being permanently tied together, are intermittently interconnectable by way of an armature m_{B4} of relay M_B cooperating with bank contacts 102 and leading to controller C_aB . A similar circuit arrangement is operative in the case of the capacitors CT_1, CT_2 and an armature m_{T4} of relay M_T engageable with bank contacts 102 and connected to controller C_aT . Via the controllers C_aB and C_aT , therefore, a voltage $V\theta_n$, which is an analogue of the maximum oscillation amplitude can be transmitted to port and starboard, respectively.

Via circuit-breaking armatures P_{B2}, P_{T2} and capacitors 103_B, 103_T, relays P_B and P_T deliver an energizing pulse to the windings of relays N_B and N_T , respectively, which lock via respective holding armatures n_{B1}, n_{T1} to normally charged capacitors 104_B, 104_T. The relays N_B and N_T therefore remain operated for a brief but definite time. Via armatures n_{B2}, n_{B3} and n_{T2}, n_{T3} , the relays N_B and N_T briefly connect the capacitors CB_1, CT_1 and CB_2, CT_2 to zero potential for discharging them.

10 In each controller C_aB and C_aT the input voltage $V\theta_n$ goes to the base of a current-amplifying transistor T_A in the case of the controller C_aT which is connected as an emitter follower in series with two load resistances r_d, r_e controlled by a selector switch 40 whereby one of the two voltages appearing at bank contacts 40_a and 40_b can be fed to a voltage divider formed by two equal and series-connected resistances r_f . Consequently, the voltage at the junction 43 of the two resistances r_f is the mean of the voltage picked up by selector 40 and the voltage at a point 41 representing one terminal of a capacitor C_a , the other terminal thereof being at ground (positive) potential. The voltage at point 43 is transmitted to the base 44 of a transistor transistor T_b whose state of conductivity controls the solenoid valve ET (FIG. 7) which, as previously explained, vents tank 2B₁ to atmosphere when energized by a pulse at time $t_r(T)$. In order that transistor T_b should become conductive, the voltage on its base 44 must reach a threshold VE (FIG. 14). Identical circuitry in controller C_aB generates an output pulse at time $t_r(B)$ to energize the solenoid valve EB of FIG. 7.

25 Capacitor C_a is charged through an adjustable resistor r_g by negative voltage transmitted via contacts $P_{T1}, 36_T$, the latter closing shortly after the time of maximum excursion of the oscillation on the particular side here concerned.

30 From the time $t_o(B)$ at which contact 36_T closes, the (negative) charging voltage of timing condenser C_a —i.e., the voltage at point 41—can be represented as a function of time by a straight line 42 (FIG. 14) if the start of the exponential charging of a capacitor is considered substantially linear. In the charging circuit of capacitor C_a a Zener diode 47 accurately determines the charging voltage for such capacitor so that the potential difference thereacross varies in a manner closely corresponding to the straight line 42.

35 Since the emitter voltage of transistor T_A is substantially the same as the voltage $V\theta_n$ developed by the network CT_1, r_c, CT_2 and applied to its base, the switch 40 can select either a voltage $V_1\theta_n$ on terminal 40₁ or a voltage $V_2\theta_n$ on terminal 40_b (see FIG. 14), both of which are analogues of θ_n and, therefore, of roll amplitude; voltage $V_1\theta_n$ can be used when the ship is stationary and voltage $V_2\theta_n$ can be used when the ship is moving; since, as has been seen, the moving-craft damping effect β_o exceeds the stationary-craft damping effect α_o , a lower analogue value can be used when the ship is moving. This voltage selection is not critical, however, for if selector 40 is kept on contact 40_b when the ship is stationary, all that will happen will be reduction correction, whereas if selector 40 is on contact 40_a when the ship is moving, the only error will be an overcorrection of low-amplitude rolling.

40 The relative magnitudes of $V_1\theta_n, V_2\theta_n$ and of VE are so adjusted that, as seen in FIG. 14, $V_1\theta_n$ and $V_2\theta_n$ are exactly equal to $2VE$ for the roll amplitudes on standstill and in motion respectively corresponding to the maximum damping effect α_o or β_o of the stabilizing tanks. Thus, the sloping line 50 in FIG. 14 represents the voltage drop across resistors r_f in the limiting case where $V_1\theta_n$ or $V_2\theta_n$ equals $2VE$. Consequently, when half the roll amplitude is greater than the damping angle, the voltage V_{40} at point 40 is greater than $2VE$ and, since the condenser voltage VC_a is zero at point 41 when maximum list to port is reached, the voltage V_{43} at point 43 and therefore on the base 44 of transistor T_b is greater than the threshold voltage VE . Tank filling is therefore initiated at an instant close to the time $t_o(B)$, thus at the desired moment as explained with reference to FIG. 12. If, however, half the roll amplitude is less than the damping angle so that the amplitude-analogue voltage V_{40} at point 40 attains, say, only a value V_m at the time

$t_o(B)$, the voltage V_{43} at junction 43 will have only the value indicated by the point 51, less than VE . Only when the voltage VC_A of capacitor C_A has reached the charging potential U_m , as shown by a sloping line 52, will the voltage VE be attained at point 43. Filling will therefore start at a time t_{rm} subsequent to the time $t_o(B)$, the separation between these two instants increasing progressively with decreasing roll amplitude.

Just as the controllers C_aB and C_aT determine the start-of-filling times for the tanks $2B_1$ and $2T_1$, respectively, the comparison circuit CV determines start-of-emptying times by interrupting the energization of these controllers at a time when the ship is passing through its mean position θ_M . To this end, the analogue voltage $V\theta_M$ developed at e_M (FIG. 13) and the analogue voltage $V\theta$ picked up by the slider 26 are fed to the bases of respective transistors T_1 , T_2 which are connected as emitter followers, with their emitters interconnected by way of the winding of polarized relay 39; two symmetrical networks 55, which comprise Zener and ordinary diodes and which shunt the winding of relay 39, limit the voltages applied thereto and absorb switching transients.

When the analogue voltage of angle θ in this balanced arrangement is greater than the analogue voltage of angle θ_M , the armature 37 engages the contact 38₂. The list is then to starboard in relation to the mean position of the ship, and controller C_aT is energized via contacts P_{71} and 36_T. Controller C_aT is deenergized—i.e., the starboard tank starts to empty—as soon as the analogue voltage of θ has decreased below its stored mean-position value, thus when the base potential of transistor T_2 has dropped below the base potential of transistor T_1 and the current flow through the winding of relay 39 is reversed so that armature 37 engages the contact 38₁.

The operation of the circuit arrangement shown in FIG. 13 will more be described in further detail. When the ship reaches its maximum excursion to one side, e.g. to starboard, first the remote pendulum contact (21₁) opens and then the proximal pendulum contact (21₂) closes. When contact 21₁ opens, relay M_B releases with the result that, through the agency of relay K_B , capacitors CB_1 , CT_1 and H_B are charged to the required potential. When contact 21₂ closes, relay M_T responds and, by attracting its armature 36_T, energizes the controller C_aT for utilization of the starboard-side analogue voltage $V\theta_n$. During the immediately preceding half period the capacitor CT_2 , along with capacitor CB_2 , had been charged and had retained its charge, the contacts m_{74} and m_{72} then being open. When contact m_{74} closes immediately after the charging of capacitor CT_1 , the voltage $V\theta_n$ is transmitted to controller C_aT and the timer (T) is registered therein. As has been seen, the time $t_r(T)$ cannot be delayed beyond the passage of the ship through its mean position. Upon such passage the contact 38₂ opens and the contact P_{72} closes so that a pulse traverses the relay N_T which discharges the capacitors CT_2 and CB_2 . The storage capacitors therefore retain their charge for about three quarter-cycles of an oscillation. In the interval between the opening of one set of contacts and the closure of the other, these capacitors can charge undisturbed to the potential representing the maximum relative swing of the pendulum 18; their discharge occurs as soon as there is certainty that the information stored in them has been used. This interval is determined by the angular play between the unit 20 and the pendulum 18. This play, by way of example, can be on the order of 0.5° and corresponds of course to the roll-amplitude threshold below which no antirolling action is initiated.

The refilling time t_r is determined in either of the controllers whenever a simultaneous closure of contacts P_{71} , 36_T or P_{81} , 36_B indicates that the maximum roll excursion to one side is greater than the stored mean angle of heel (θ_M). If this is exceptionally not the case, the antiroll system does not operate. The time t_r corresponds to the start of filling of the tank on the corresponding side, such filling ceasing upon the start of emptying at the time t_r determined by the movement of the armature 37.

The oscillation period T may vary, e.g. because of ship load-

ing or of the swell, but this does not impede the operation of the system, which adapts itself to the new period, for the state of charge of the storage condensers decreases substantially linearly in time so that the analogue of swing angle θ_n for each side varies with time as indicated by the sloping lines 60, 61, 62 in FIG. 14.

If S denotes the voltage threshold corresponding to the angular play between the reference unit 18 and the mobile unit 20, the longest period $T_o/4$ for which the system can operate is determined by a sloping line 64 and its horizontal extension 65 intersecting the charging curve 42. If the period decreases to a value $T < T_o$, the voltage given by the intersection of threshold line 60 with an ordinate $V_3\theta_n$ corresponds to the same minimum roll angle. However, an analogue voltage V_m for a given roll angle, represented by line 61, changes to a higher voltage V'_m for the same angle upon a decrease of the period from T_o to T . As shown by a sloping line 66, the start-of-filling time advances concurrently from t_{rm} to t'_{rm} . Thus, any reduction in the length of the oscillatory period is compensated by a more rapid response of the roll stabilizer.

The simplified system shown in FIG. 17 is designed for cases where it is not necessary to determine the ship's mean position between two consecutive extreme angles of heel, its stabilizer including but one pair of tanks operating only on heavy rolling. A relay winding M_1 associated with one of the two sides of the ship (its symmetrical counterpart not being illustrated) is controlled as before by one of the contacts (21₁) of the rocking assembly 18, 20 and operates a reversing armature 68 forming part of the controller for the particular side concerned; when in its solid-line position, armature 68 enables a capacitor 69 to be charged by a stabilized voltage V . The capacitor circuit is closed via a tap on a voltage divider 71, 72. When contact 68 is in its dotted line position, capacitor 69 discharges into a circuit comprising, in parallel, a relay winding 73 and a resistance 74.

Via its armature 79 the relay winding controls, as in the preceding embodiment, the energization of the solenoid valve controlling tank filling (or the operation of equivalent antiroll means) corresponding to the particular side concerned; also, the relay 73, 79 is so designed that a drop in the voltage across its winding 73—i.e. across capacitor 69—below a critical value V_s (FIG. 18) releases the armature 79.

If the total resistance and therefore the time constant of the charging circuit of capacitor 69 is twice that of its discharging circuit, the slope 75a (FIG. 18) at the start of the charging curve for capacitor 69 is half the absolute value of the opposite slope 76a of its discharging curve 76. Consequently, since each of the contacts 21₁, 21₂ stays closed for substantially the time $T/2$, charging stops after that time at the point 77 and discharging restores the voltage across the relay winding to the value V_s during the next time interval $T/4$, whereupon the voltage V_s is maintained across capacitor 69 by a diode 80 in parallel therewith. Contact 79 is therefore kept closed for a time $T/4$ during each oscillation period T , and when the reversing switch 68 next returns to its solid-line position in the following period, charging of the capacitor 69 restarts from the potential level V_s .

Thus, the relay circuit of FIG. 17 including condenser 69 acts as a delay network translating a closure of contact 21₁ during the interval $0 - 1/4$ into a closure of contacts 79 in the interval $T/2 = 3T/4$. This delay of corrective action by about half a cycle, measured from the timing signal given by the opening or closure of contacts 21₁, 21₂, is the same as that between the charging of the storage condensers in FIG. 13 and the utilization of the stored charge by controllers C_aB and C_aT .

FIG. 19 relates to a case in which the stabilizing means is an aileron having either a variable inclination (e.g. pitch angle) I or a fixed inclination and a variable effective length L (FIG. 4) transverse to the craft. The roll is represented as a damped sinusoidal line 78, the assumption being that the antiroll means becomes effective when the swing already has reached certain minimum amplitude. The aileron-extension signal can be generated at times $t_o(B)$ and $t_o(T)$, under the control of the

units 18 and 20, whereas the inclination I or the effective length L can be under the control of the parameter $V\theta_n$ representing the peak amplitude.

FIG. 20 relates to the case of ailerons of invariable efficiency (constant inclination and effective length), the control parameter being the time t_e for which the aileron is extended. With a system of the kind shown in FIG. 17, aileron-extension time t_e can coincide with a quarter-cycle of the oscillation; alternatively, for still greater effectiveness, the aileron can be made operative at a variable starting time t_r determined by the respective controller C_aB or C_aT shown in FIG. 13. Maximum damping prevails of course when the aileron is always extended for half a cycle, as in the case of FIG. 19.

If only very large rolls are to be damped, the control system can be limited to the relatively movable elements 18 and 20 determining, as the only controlling parameters, the consecutive instants $t_o(B)$, $t_o(T)$ which are established by the alternate operation of the contacts 21₁ and 21₂, and which mark the start and the end of successive half-periods.

The embodiments hereinbefore described can of course be modified, by the substitution of equivalent structure and circuitry, without departing from the spirit and scope of this invention.

We claim:

1. In a craft subject to rolling motion about a longitudinal axis and equipped with stabilizer means for counteracting such rolling motion, the combination therewith of:
    - a reference member aboard the craft in the form of a weighted rod suspended from a mounting with a pivotal axis parallel to said longitudinal axis;
    - a coacting member mounted aboard the craft for lateral angular entrainment thereby, said coacting member having a pair of arms bracketing said rod;
    - cooperating circuit means on said members for generating timing signals during predetermined relative positions thereof coinciding with maximum lateral excursions of the craft with reference to said axis, said circuit means including a first set of normally open contacts on said rod and on one of said arms and a second set of normally open contacts on said rod and on the other of said arms, said sets of contacts being alternately closable in symmetrical relative positions of said arms and said rod, said arms being provided with frictional bearing means supporting same for swinging movement about a line parallel to said longitudinal axis, the friction of said bearing means being low enough to let either of said arms come to rest against said rod upon an incipient swing of the craft to a respective side whereby the corresponding set of contacts remains closed for substantially half a rolling cycle; and
    - actuating means connected to said circuit means for periodically making said stabilizer means effective in response to said timing signals.
  2. The combination defined in claim 1 wherein said actuating means comprises a delay network for translating closure of either of said sets of contacts into corrective actuation of said stabilizer means substantially half a rolling cycle later.
  3. The combination defined in claim 2 wherein said delay network includes first relay means connected to operate in response to closure of either of said sets of contacts, condenser means chargeable by said first relay means in the operated condition thereof, and second relay means connected for operation by a discharge current from said condenser means in the unoperated condition of said first relay means.
  4. The combination defined in claim 3 wherein said delay network further includes a charging circuit for said condenser means and a discharge circuit for said condenser means
- 5 10 15 20 25 30 35 40 45 50 55 60 65
5. The combination defined in claim 3 wherein said actuating means further comprises capacitive means for storing a charge applied thereto by said second relay means upon operation of the latter, controller means for said stabilizer means, and switch means controlled by said first relay means upon reoperation thereof for applying the stored charge from said capacitive means to said controller means.
  6. The combination defined in claim 5 wherein one of said members is provided with a generator of variable voltage depending upon the heel angle of the craft with reference to the vertical, said capacitive means being connectable by said second relay means to said generator for varying said stored charge in accordance with said variable voltage, said condenser means having a discharge circuit through said second relay means with a time constant which is short compared with a rolling cycle.
  7. The combination defined in claim 6 wherein said capacitive means comprises two pairs of identical capacitors and said generator includes two complementary voltage sources each connectable by said switch means to a respective capacitor of each pair at the end of a respective half-cycle, said controller means comprising two controllers for operating respective sections of said stabilizer means to correct listing to corresponding sides, each pair of capacitors being provided with a bridging voltage divider having two normally disconnected halves interconnectable by said switch means for transmission to a corresponding controller of the mean of the charges stored.
  8. The combination defined in claim 7, further comprising a comparison circuit connected to receive from said generator an analogue voltage proportional to the mean heel angle of the craft between successive lateral excursions, together with the output of one of said sources, and third relay means responsive to said comparison circuit for transmitting an activating signal to either of said controllers in dependence upon the relative magnitude of said output and said analogue voltage.
  9. The combination defined in claim 8 wherein said sections of said stabilizer means each comprise a main tank and an auxiliary tank, first valve means responsive to a corresponding controller for alternately filling and draining said main tank during part of a rolling cycle, and second valve means responsive to said analogue voltage for filling said auxiliary tank to an extent determined by said mean heel angle.
  10. The combination defined in claim 8 wherein each of said controllers includes a timing condenser chargeable at a controlled rate in the presence of said activating signal and signaling means responsive to a predetermined relationship between the charge on said timing condenser and the mean charge of the associated pair of capacitors transmitted thereto by said switch means.
  11. The combination defined in claim 10 wherein each controller further includes switchover means for modifying the magnitude of said mean charge prior to comparison with the charge on said timing condenser.
  12. The combination defined in claim 7 wherein said complementary voltage sources comprise a pair of arcuate potentiometer tracks rigid with the craft and a pair of contactors on said rod respectively sliding along said tracks.
  13. The combination defined in claim 1 wherein said actuating means includes at least one amplifier with a pair of transistors of opposite conductivity types having emitters interconnected by a low-impedance circuit and having collectors connected to points of fixed potentials.

through said second relay means, said charging circuit having a time constant substantially twice that of said discharge circuit whereby said second relay means operates for substantially a quarter of a rolling cycle.

5. The combination defined in claim 3 wherein said actuating means further comprises capacitive means for storing a charge applied thereto by said second relay means upon operation of the latter, controller means for said stabilizer means, and switch means controlled by said first relay means upon reoperation thereof for applying the stored charge from said capacitive means to said controller means.
6. The combination defined in claim 5 wherein one of said members is provided with a generator of variable voltage depending upon the heel angle of the craft with reference to the vertical, said capacitive means being connectable by said second relay means to said generator for varying said stored charge in accordance with said variable voltage, said condenser means having a discharge circuit through said second relay means with a time constant which is short compared with a rolling cycle.
7. The combination defined in claim 6 wherein said capacitive means comprises two pairs of identical capacitors and said generator includes two complementary voltage sources each connectable by said switch means to a respective capacitor of each pair at the end of a respective half-cycle, said controller means comprising two controllers for operating respective sections of said stabilizer means to correct listing to corresponding sides, each pair of capacitors being provided with a bridging voltage divider having two normally disconnected halves interconnectable by said switch means for transmission to a corresponding controller of the mean of the charges stored.
8. The combination defined in claim 7, further comprising a comparison circuit connected to receive from said generator an analogue voltage proportional to the mean heel angle of the craft between successive lateral excursions, together with the output of one of said sources, and third relay means responsive to said comparison circuit for transmitting an activating signal to either of said controllers in dependence upon the relative magnitude of said output and said analogue voltage.
9. The combination defined in claim 8 wherein said sections of said stabilizer means each comprise a main tank and an auxiliary tank, first valve means responsive to a corresponding controller for alternately filling and draining said main tank during part of a rolling cycle, and second valve means responsive to said analogue voltage for filling said auxiliary tank to an extent determined by said mean heel angle.
10. The combination defined in claim 8 wherein each of said controllers includes a timing condenser chargeable at a controlled rate in the presence of said activating signal and signaling means responsive to a predetermined relationship between the charge on said timing condenser and the mean charge of the associated pair of capacitors transmitted thereto by said switch means.
11. The combination defined in claim 10 wherein each controller further includes switchover means for modifying the magnitude of said mean charge prior to comparison with the charge on said timing condenser.
12. The combination defined in claim 7 wherein said complementary voltage sources comprise a pair of arcuate potentiometer tracks rigid with the craft and a pair of contactors on said rod respectively sliding along said tracks.
13. The combination defined in claim 1 wherein said actuating means includes at least one amplifier with a pair of transistors of opposite conductivity types having emitters interconnected by a low-impedance circuit and having collectors connected to points of fixed potentials.
